UNITED STATES PATENT OFFICE.

MAJOR H. WEERS, OF PEORIA, ILLINOIS.

DEVOTIONAL DEVICE.

Application filed May 7, 1925. Serial No. 28,628.

This invention relates to a devotional device or stand more particularly of service at Catholic funerals.

The invention pertains to a combined 5 crucifix, a font for containing holy water, receptacles for vigil lights, and a receiver or container for so called spiritual bouquets all combined in a single unit structure.

In the appended drawing showing a preferred arrangement of my invention:—

The character 1 designates the base or body of the device, preferably a casting including legs 2 forming a tripod. Uprising from what may be termed the rear side of 20 the body is a standard 3 having a cross-arm 4, the whole forming a cross for supporting a corpus, not shown.

The said base or body is provided at its forward portion with a font 5 of any preferred form of outline as viewed in plan but preferably shallow and of some considerable area.

Rearward of and lying between the font 5 and the standard 3 is a receptacle 6 for 30 containing spiritual bouquets which, it may be known, are in the form of cards 7 for deposit by the mourners. This said receptacle 6 is of rectangular form, as shown in this instance, and lies well above the 35 level of the said font 5, the rear wall 8 of the latter forming the front wall of said receptacle by extending the same upwardly. This said wall where it forms the front of the receptacle is of open construction as 40 denoted by the openings or windows 9 through which the cards 7 may be observed. That is to say, the receptacle 6 since lying well above the font 5 can be readily noticed by the mourner, the possessor of a card and 45 the cards therein can easily be seen through the said openings or windows.

At each end of the receptacle and nearly level therewith is a container or cup 10 for the reception of a vigil light, not shown, 50 these completing an arrangement having all of the advantages and uses for a funeral service as regards the devotional attitude of the mourner.

Although the receptacle 6 is placed above 55 the level of the top edge of the font 5 so that it may be readily seen and reached for the deposit of the cards 7, all by preference, it may be otherwise located.

At funerals attended by and under the direction of those of the Catholic faith the 60 so called spiritual bouquets in the card form mentioned are usually placed by the mourners in haphazard manner upon the casket or other support which cards present a very untidy appearance, even falling to the 65 floor and becoming scattered about the place of service. It is therefore the desire and aim to remedy this result by providing a common receptacle for the cards which are associated with the other devotional and 70 symbolic devices usually employed on such occasion.

Having thus described my invention, I claim:—

1. A device for devotional purposes including, in combination a font for containing water, a receptacle rearward of and arranged at a higher level than the font and having a length substantially coextensive with the latter, the bottom of 80 the receptacle being substantially at the height of the top of the font, the front wall of the receptacle being provided with openings through which to view the interior, and said front wall being extended downwardly 85 and closed to form the rear wall of said font, and a container for a vigil light disposed at each end of the receptacle outside the same, their tops being substantially at the same level with such receptacle. 90

2. A device for devotional purposes including a structure of a single part having a font for containing water, a receptacle rearward of and arranged at a higher level than the font and having a length substantially coextensive with that of said font, the bottom of the same being substantially at the height of the top of the font, the front wall of said receptacle being of open form whereby the interior may be viewed and said 100 front wall being extended downwardly forming the rear wall of said font, a container for a vigil light disposed at each end of said receptacle outward from the same and rearward of the font, and a crucifix 105 erected behind the receptacle and uprising from the rear wall thereof.

In testimony whereof I affix my signature.

MAJOR H. WEERS.
